WILLIAM L. DENCH, OF PELHAM, NEW YORK, ASSIGNEE, BY MESNE ASSIGNMENTS, TO
UNDEDWOOD COMPUTING MACHINE COMPANY, OF NEW YORK, N. Y., A CORPORA-
TION OF NEW YORK.

COMBINED TYPE-WRITING AND COMPUTING MACHINE.

1,196,732.

Specification of Letters Patent. Patented Aug. 29, 1916.

Application filed March 21, 1912. Serial No. 325,362.

To all whom it may concern:

Be it known that I, WILLIAM L. DENCH, a citizen of the United States, residing in Pelham, in the county of Westchester and 5 State of New York, have invented certain new and useful Improvements in Combined Type-Writing and Computing Machines, of which the following is a specification.

This invention relates to combined type-writing and computing machines, of the kind in which numeral keys are employed to set up pins or devices which determine the extent to which the dial wheels are to be rotated; the rotation of all the wheels 15 being effected simultaneously by means of a general operator.

In some combined typewriting and computing machines of this character, the general operator has been power-driven, and 20 a controlling device has been connected to the carriage of the typewriter, to cause the general operator to work as soon as the carriage has proceeded far enough to complete the writing of a number, that is, after 25 the carriage has passed the units column or place.

One of the objects of the present invention is to avoid any difficulty or any failure on the part of the general operator, which 30 may arise from the failure of the operative of the machine to feed the carriage along past the units position, in which case the number written upon the work sheet would not be carried into the computing wheels.

Another object is to avoid the objection which may arise from the fact that the carriage of a typewriter is often released from 35 its letter-feeding mechanism, and run rapidly along the machine, and hence is liable to start the general operator into action unnecessarily.

To these and other ends, I have contrived to render the action of the general operator independent of the movement of the carriage, although such action of the general operator will usually occur upon the return of the carriage to begin a new line of writing. I connect to the usual line-space lever of the typewriter, a contrivance which is 45 normally idle, but which is rendered effective at every stroke of the line-space lever, for causing the motor to actuate the general operator of the computing mechanism. Since in making a computation it is neces-

sary to write one number beneath another, and hence necessary to line-space the paper after the writing of every number, it will be seen that the liability of a number being written on the work sheet without being carried into the computing wheels, is minimized or avoided; while at any time, the carriage may be run freely in either direction without liability of starting the computing operator into action.

There is usually a normally open clutch provided between the motor and the general operator of the computing mechanism, and a key is usually provided at the keyboard for causing said clutch to close, so that the general operator may be driven by the motor; and provision is usually made for opening the clutch at the conclusion of a cycle of operations of the general operator. I have provided a connection from the line-space lever on the typewriter carriage to 75 said clutch, such that an operation of the lever will cause the clutch to close.

In the preferred form of the invention, the connection is such, that the retaining of the line-space lever at the end of its stroke, does not cause the clutch to remain closed. In other words, there must be repeated strokes of the line-space lever in order to effect repeated operations of the general operator. Hence the continued as pressure which is usually exerted upon the line-space lever during the return of the carriage to begin a new line, does not create an objection to the use of said lever for the purpose of closing said clutch. It will thus be seen that by the actuation of a single lever, there are performed the various operations of line-spacing, carriage-returning, and rotation of the computing wheels.

The clutch employed for the general operator is usually the kind that tends normally to close, but is restrained by a dog or latch. This restraining dog is withdrawn by the movement of the line-space lever; connection being made by means of linkages 100 from the line-space lever to said restraining dog, so that an actuation of said lever either at the end of a line of writing, or at any other point in the travel of the carriage, will withdraw the dog, enabling the clutch to 105 close, and the general operator to be actuated. This relieves the typist from the necessity of separately operating the usual

clutch-closing key aforesaid, whenever it is desired, as the mere operation of the line-space lever effects the starting of the general operator.

5. Other features and advantages will hereinafter appear.

In the accompanying drawings, Figure 1 is a fragmentary perspective view, showing the connection between the line-space lever 10 and the means for controlling the operation of the general operator. Fig. 2 is a detail view partly in section, showing the relation of the trip to the line-space lever. Fig. 3 is a fragmentary top plan view, showing 15 the means actuated by the line-space lever to control the general operator of the computing mechanism. Fig. 4 is a side view in elevation with parts in section. Fig. 5 is a spread perspective view, showing details 20 of the trip.

Referring more particularly to the separate parts of this invention as embodied in the form shown in the drawings, 1 indicates the keys of the typewriter which are secured 25 to key levers 2 and operate through the intermediary of bell cranks 3, type bars 4 to swing the latter upwardly and rearwardly against the front side of a platen 5 mounted to rotate in bearings on a platen frame 6, 30 which in turn is mounted on a carriage 7. The movement of the carriage may be controlled in the usual manner common to the Underwood typewriting machine at each actuation of a key by an escapement mechanism indicated in general at 8.

The platen 5 may be rotated in the usual manner by hand by means of a knob 9; and it is also rotated for the purpose of line-spacing. In the form shown, the platen is 40 provided with a ratchet wheel 10 engageable by a pawl 11 pivotally mounted on a sliding plate 12. Pawl 11 is provided with a toe 13 which engages an adjustable rest 14 to vary the extent of rotation of the platen by the 45 pawl. The platen is held in any adjusted position by a spring-pressed detent 15. The plate 12 is normally held in a forward position by means of a spring 16, so that a right angle extension 17 thereon may be engaged 50 by a short arm 18 of a pivotally mounted line-space lever 19. The arm 18 contacts with the extension 17 so that the platen and its frame will be free to move up and down relative to the line-space lever 19 for the 55 purpose of changing from lower to upper case characters without interrupting the connection. As the carriage 7 moves step-by-step under the control of escapement 8, one or more tappets 20 provided thereon 60 come successively into engagement with a series of jacks 21, so as to rock them about their intermediate pivots, whereby the rear ends thereof are forced down to depress thrust links 22. These thrust links 22 engage at their lower ends with linkages 23,

whereby denominational column bars 24 are raised successively to correspond with the denominational columns of the work sheet at the printing point.

It will be noted in passing that the linkages 23 are of the transposing type so that the jack 21 at the extreme right of a group of jacks will actuate the column bar 24 at the extreme left of a nest of column bars. Each of the column bars 24 is provided with 70 a series of nine settable pins 25 which determine the subsequent extent of movement of the bars 24. When one of the column bars 24 is raised, it brings its row of pins above the rest of the pins in the nest, whereby one of the pins will be projected downwardly below its fellows by one of a set of linkages 26 which are operated from the numeral keys of the typewriter by stems 27 which engage projecting arms 28 connected 80 to associated linkages. The arrangement is such that there is one linkage for each numeral key from "1" to "9", so that the actuation of a numeral key will set a pin 25 corresponding thereto, thereby determining the 90 extent of movement which a particular bar in elevation will subsequently have, according to the value of the numeral key struck.

Bars 24 are provided at their forward ends with racks 75 engaging wheels 76 connected to numeral-bearing dial or computing wheels 77 which will exhibit the calculation run up by the numeral keys through an aperture 78 in the casing 79. When the numeral keys have been actuated to write a 100 series of digits corresponding to units, tens, etc., of a number to be calculated, the valuation of said number will have been concomitantly set on the nest of computing pins 25, so that certain of these pins, one 105 for each bar 24, will project down below the bars into the path of a cross-bar 29 on a general operator 30.

The general operator 30 is provided with a rack bar 31 whereby it may be operated 110 manually through the intermediary of a pinion 32 which meshes with the rack bar and which also meshes with the sector gear 33' rotatable by means of a hand crank 34'. For many purposes, however, it is preferable 115 to actuate the general operator 30 by means of a source of power such as the electric motor 33. The connection between the electric motor 33 and the general operator, however, is preferably of such a type that the motor 33 may rotate independently of the operation of the machine, and only actuate the general operator 30 at such time as is necessary and then only for one complete 120 cycle of its movement. This connection may 125 be of any suitable character, such as that shown and described in the application of Frederick A. Hart, No. 596,451, filed December 9, 1910, wherein the motor is provided with a shaft 34 having a worm 35 130

meshing with a worm wheel 36; and further wherein the general operator is connected to a cross head 37 guided for movement by having projecting rods 40 engaging in guiding stockets 38 in a casing 39.

The cross head 37 is connected so as to be reciprocated from a crank shaft 41 by a crank and slide connection indicated in general at 42. The crank shaft 41, however, is normally disconnected from the worm wheel 36, but connectible thereto by a clutch 43, the particular form of which is not a part of this invention, but it may be similar to that shown in the above-mentioned application, No. 596,451, filed December 9, 1910. It is sufficient to say, however, that the clutch is provided with a connection-controlling element 44 shown in the form of a ring having a projecting tooth 45 which, when obstructed in its movement, will cause a disconnection of the crank shaft 41 from the worm wheel 36, so that the operative connection between the general operator 30 and the electric motor 33 will be interrupted. To obtain this disconnection there is provided a disconnector 46 shown in the form of an obstructing pin normally held in a depressed or restraining position by means of a spring 47. The obstruction 46 may be raised from its position in the path of the tooth 45 by means of a lever 48 which is pivoted intermediate its ends, and engages at one end in a slot 49 provided in the obstructing pin 46. To cause a cycle of movements of the general operator 30 separately, there may be provided a control key 50 which, when depressed, is adapted to swing down a pivotally mounted lever 51 which projects above one arm of the lever 48, so as to raise the obstruction 46 from the path of the tooth 45.

For the purpose of removing the obstruction 46 and enabling the operation of the general operator 30 by the motor 33 when the platen is spaced and the carriage returned for a new line, there is provided in the path of movement of the line-space lever 19 a trip 52 which is mounted to rock on a fixed pin 53, so that it may be swung by the line-space lever 19 to cause an arm 54 thereof to rock a shaft 55 by engagement with an arm 56 thereon. The rock shaft 55 is also provided with a finger or arm 57 which overlies a bail 58 secured to a rock shaft 59. The position of the finger 57 on the carriage 7 and the linear magnitude of the bail 58 are such that finger 57 will overlie the bail 58 in any position of the carriage 7, whereby the actuation of the line-space lever 19 to return the carriage or space the platen, will be effective in any position of the carriage, to rock the shaft 59. The rock shaft 59 is provided with an arm 60 which connects it to the lever 48 through the intermediate of a link 61, so that when the line-

space lever 19 is actuated, the obstruction 46 will be removed from the path of the tooth 45. Inasmuch as the motor 33 will continue to reciprocate the general operator 30 as long as the disconnector 46 is held in its raised position, it is desirable to have the connection between the line-space lever 19 and the disconnector 46 of a single acting type. For this purpose the trip 52, as will be seen more clearly in Figs. 2 and 5, is of a peculiar structure. Trip 52 is provided with an arm 62 which projects in the path of the line-space lever 19, and is beveled at its engaging surface so that when the line-space lever passes by the trip, it will slip off the end of the arm 62. A spring 63 engaging the other arm 54 will raise the trip to its normal position with the arm 62 projecting upward. It will thus be seen even if the line-space lever 19 should be held in its actuated position for a considerable period, as would be the case in returning the carriage, the obstructing disconnector 46 will be only raised long enough to permit the tooth 45 to pass beyond it, when it will be dropped into a disconnecting position so as to prevent more than one complete cycle of movements of the general operator 30. The spring 63 forces the arm 54 against a stop pin 64 so as to properly position the trip for subsequent actuation by the line-space lever 19. It will be evident that this necessitates means for permitting the line-space lever 19 to return to its original position after having been actuated. For this purpose the trip 52 is formed in two parts loosely mounted on the pin 53. The part which carries the arm 54 is provided with a shoulder 65 underlying a shoulder 66 on the part which carries the arm 62. The part which carries the arm 62 is normally held with the shoulder 66 in engagement with the shoulder 65 by means of a spring 67, so that a movement of the arm 62, due to the initial actuation of the line-space lever 19, will be transmitted to the arm 54; but at the same time, the arm 62 will be permitted to move backwardly against tension of the spring 67 to allow the line-space lever 19 to snap by on its return movement.

The operation of the device will be readily understood when taken in connection with the above description. The numeral keys 1 are struck according to any predetermined sequence, whereby they will simultaneously cause a printing of the corresponding numbers on the work sheet on the platen, and cause an indexing of the calculation by a setting up of the pins 25. If the numbers are being written in several distinct columns across the sheet, the calculation may be run up on the dial wheels by an actuation of the control key 50 for points preceding the end of the line. At the end of the line when it is necessary to space the platen, to return

the carriage and carry up the computation, the line-space lever 19 can be thrown so that it will rotate the platen, and before it reaches the limit of its throw, will have 5 rocked the trip 52 and snapped over the projecting arm 62 thereof, so that the obstructing pin 46 will have been raised from the path of the tooth 45 a sufficient time to permit the connection-controlling element to 10 spring forward and complete the operative driving connection between the motor 33 and the general operator 30. The general operator reciprocates the column bars an extent according with the particular pins 15 set, and these bars in turn rotate the dial or computing wheels corresponding amounts. Even if the line space lever 19 should be held in its actuated position, the spring 63 will have returned the trip 52 to its normal 20 position enabling the obstruction 46 to disconnect the general operator from the motor after one complete cycle. The biparted form of the trip 52 enables the passive return of the line space lever 19.

25 Variations may be resorted to within the scope of the invention, and portions of the improvements may be used without others.

Having thus described my invention, I claim:

30 1. The combination of a typewriting mechanism including a traveling platen carriage and a line space means for said platen, a computing mechanism having a general operator, and single acting mechanism momentarily operated and released by said line space means during each actuation of said line space means for enabling solely one complete cycle of movement of said general operator.

40 2. The combination with a typewriting mechanism including a carriage, a platen on said carriage, and line space mechanism for said platen, of a computing mechanism including a general operator, normally disconnected driving connections for said general operator, a lever for enabling the operative connection of said driving connection to said general operator, a link connected to said lever, a bail running alongside of said carriage, and connected to said link, and means operated by said line space mechanism, connected to move with said carriage, and overlying said bail so as to actuate the same at any point in the movement of said carriage.

50 3. The combination with a typewriting mechanism including a carriage, a platen on said carriage, and line space mechanism for said platen, of a computing mechanism including a general operator, a bail positively connected to said general operator and extending alongside of said carriage, said carriage being movable relatively to said bail, and means momentarily operated and released by said line space mechanism con-

nected to said carriage and arranged to operate said bail in any position of said carriage.

4. The combination with a typewriting mechanism including a carriage, a platen on 70 said carriage, and line space mechanism for said platen, of a trip located in the path of a certain movable part of said line space mechanism to be momentarily engaged and then released thereby, a finger connected to 75 said trip, a computing mechanism including a general operator, means enabling the actuation of said general operator, and a bail positively connected to said enabling means and actuated by said finger to start 80 the action of said enabling means.

5. The combination with a typewriting mechanism including a carriage, a platen on 85 said carriage and line space mechanism for said platen, of a computing mechanism including a general operator, enabling means for causing the actuation of said general operator, and means causing the actuation of said enabling means, momentarily in contact with a certain movable part of said line space mechanism, so as to be momentarily actuated thereby and then released intermediate the limits of movement of said part.

6. The combination with a carriage, of a 95 platen on said carriage, computing mechanism including a general operator and enabling means for causing a cycle of movement of said general operator, single acting means for starting the action of said enabling means, line space mechanism for said platen adapted to momentarily operatively engage and then release said single acting means, to cause solely one complete cycle of movement of said general operator, and a 105 spring for returning said single acting means to its normal position after each actuation.

7. The combination with a carriage, of a 110 platen on said carriage, line space mechanism for said platen, a computing mechanism including a general operator, a source of power, an automatic clutch tending to connect said general operator to said source of power, a disconnector for said automatic 115 clutch, a trip located in the path of a certain movable part of said line space mechanism, a finger connected to said trip, a bail extending alongside of said carriage so as to be operated by said finger at any point in 120 the movement of said carriage, and operative connections between said bail and said disconnector.

8. The combination with a carriage, of a 125 platen on said carriage, line space mechanism for said platen, a computing mechanism including a general operator, a source of power, an automatic clutch tending to connect said general operator to said source of power, a disconnector for said automatic 130

clutch, a trip located in the path of a certain movable part of said line space mechanism, a finger connected to said trip, a bail extending alongside of said carriage so as to be operated by said finger at any point in the movement of said carriage, and operative connections between said bail and said disconnector, said trip being formed so as to permit the return movement of said part of said line space mechanism without disturbing said disconnector.

9. The combination with a platen, of a line space mechanism for said platen including a movable lever, a trip located intermediate the limits of travel of said lever so as to be momentarily actuated and then released thereby, a computing mechanism, and connections between certain parts of said computing mechanism and said trip enabling the actuation of said certain parts at the actuation of said trip by said lever.

10. The combination with a platen, of a line space mechanism for said platen including a movable lever, a trip located intermediate the limits of travel of said lever so as to be momentarily actuated thereby, a computing mechanism, connections between certain parts of said computing mechanism and said trip, enabling the actuation of said certain parts at the actuation of said trip by said lever, and a spring for returning said trip to its normal position when said lever has passed by after actuating said trip.

11. The combination with a platen, of a line space mechanism for said platen including a movable lever, a trip located intermediate the limits of travel of said lever so as to be momentarily actuated thereby, a computing mechanism, connections between certain parts of said computing mechanism and said trip, enabling the actuation of said certain parts at the actuation of said trip by said lever, and a spring for returning said trip to its normal position when said lever has passed after actuating said trip, said trip comprising a plurality of relatively movable parts enabling the return of said lever without interfering with the parts of said computing mechanism.

12. The combination with a platen, of a line space mechanism for said platen including a movable lever, a trip located intermediate the limits of travel of said lever, so as to be momentarily actuated thereby, a computing mechanism, connections between certain parts of said computing mechanism and said trip, enabling the actuation of said certain parts at the actuation of said trip by said lever, a spring for returning said trip to its normal position when said lever has passed after actuating said trip, said trip comprising a plurality of relatively movable parts enabling the return of said lever without interfering with the parts of said computing mechanism, and a spring

means for yieldingly holding the parts of said trip in operative contact.

13. The combination with a typewriting mechanism, including a platen carriage and a line-space lever on said carriage for said platen, of a computing mechanism, including a general operator and means for actuating said general operator, and a single-acting mechanism mounted on said carriage lying in the path of said line-space lever so as to be actuated thereby at the actuation thereof and escape from said line-space lever after having been actuated, said single-acting mechanism acting to enable the drive of said general operator by said actuating means.

14. The combination with a typewriting mechanism, including a platen and a line-space lever for said platen, of a computing mechanism, including a general operator and means for actuating said general operator, and a snap connection momentarily subjecting the drive of said general operator by said actuating means to the control of said line-space lever at an actuation thereof, and escaping from said line-space lever after having been manipulated thereby.

15. The combination with a typewriting mechanism, including a platen and a line-space lever for said platen, of a computing mechanism, including a general operator and means for actuating said general operator, a trip lying in the path of said line-space lever to be actuated thereby and acting to control the drive by said actuating means of said general operator, said trip being biparted and having interengaging shoulders on each of said parts to prevent relative movement of said parts in one direction, and spring means for permitting relative movement of said parts in the opposite direction, one of said parts being arranged to be actuated by said line-space lever and the other of said parts being connected to control the drive of said general operator by said actuating means.

16. The combination with a typewriting mechanism, including a traveling carriage, a platen on said carriage and a line-space lever for said platen, of a computing mechanism, including certain operating parts and a source of power for driving said parts, connections for controlling the drive of said parts by said source of power, a finger mounted on said carriage adjacent to the plane of the printing point of said carriage and engaging said connections at any point in the movement of the carriage, so as to enable the control of the actuation by said source of power of said certain operating parts from said carriage, and a trip lying in the path of said line-space lever to be actuated thereby and connected to actuate said finger.

17. The combination with a typewriting

- mechanism, including a traveling carriage, a platen on said carriage and a line-space lever for said platen, of a computing mechanism, including certain operating parts and 5 a source of power for driving said parts, controlling mechanism for governing the drive of said operating parts by said source of power, a trip mounted on said carriage and lying in the path of said line-space lever to be momentarily actuated thereby and then released, and universal connections between 10 said trip and said controlling mechanism enabling said line-space lever to govern the drive of said operating parts by said source of power at any point in the movement of 15 said carriage.
18. The combination with a typewriting mechanism, including a platen, a traveling carriage and line-space mechanism for 20 said carriage of a computing mechanism, including certain operating parts and a motor for driving said parts, and controlling connections between said line-space mechanism and said motor enabling a single actuation 25 of said parts by said motor and preventing more than one actuation of said parts by said motor for a single actuation of said line-space mechanism.
19. In a combined typewriting and computing machine, the combination with a traveling carriage and a general operator, of a motor for driving said general operator, a rock shaft extending adjacent said carriage for connecting said motor and said 30 operator, a swinging line-space lever mounted on said carriage, a rock shaft on said carriage operable to operate the first-named rock shaft, and a trip pivoted on said carriage and operable by said line-space lever 35 as it passes the trip, to operate the second named rock shaft and cause the latter to actuate the first-named rock shaft to start the general operator.
20. In a combined typewriting and computing machine, the combination with a general operator, a motor for driving it, and a traveling carriage, of a line-space lever for said carriage, a rock shaft carried on 40 said carriage for connecting said motor and said general operator, an arm lying in the path of said line-space lever when it is operated, a rock shaft operating arm, and a connection between said arms whereby the line-space lever in its movements operates 45 one arm by the other, but on its return movement is ineffective to operate the rock shaft operating arm.
21. In a combined typewriting and computing machine, the combination with a general operator and a motor for driving it, of a traveling carriage, a rock shaft mounted 50 on said carriage and connected to start said motor to drive said operator, a line-space lever on said carriage, an arm lying in the path of said line-space lever for operation 55 thereby, a rock shaft operating arm, a common element on which said arms are journaled, said arms having co-acting shoulders whereby they are moved together during the effective movement of the line-space lever, and a spring for normally holding the lever-operated arm in effective position.
22. In a combined typewriting and computing machine, the combination with a general operator and a motor for driving it, of 60 a traveling carriage, a rock shaft mounted on said carriage and connected to start said motor to drive said operator, a line-space lever on said carriage, an arm lying in the path of said line-space lever for operation thereby, a rock shaft operating arm, a common element on which said arms are journaled, said arms having co-acting shoulders whereby they are moved together during the effective movement of the line-space lever, a 65 spring for normally holding the lever-operated arm in effective position, and a stop limiting the movement of the rock shaft operating arm.
23. In a combined typewriting and computing machine, the combination with a general operator and a motor for driving it, of 70 a traveling carriage, a rock shaft mounted on said carriage and connected to start said motor to drive said operator, a line-space lever on said carriage, an arm lying in the path of said line-space lever for operation thereby, a rock shaft operating arm, a common element on which said arms are journaled, said arms having co-acting shoulders whereby they are moved together during the effective movement of the line-space lever, a 75 spring for normally holding the lever-operated arm in effective position, and a stop limiting the movement of the rock shaft operating arm.
24. The combination with a typewriting mechanism including a traveling platen carriage and line-space means, of a computing mechanism having a general operator, a lever on said carriage for causing a single complete cycle of movement of said operator, and a mechanism operated by said line-space means for momentarily operating said lever and then releasing it.
25. In a combined typewriting and computing machine, the combination with a traveling carriage and a rotatable platen on said carriage, of numeral keys, a line-space mechanism for said platen, devices in which 80 numbers are temporarily set up by said keys, computing wheels into which numbers so set up are carried by said devices, a motor for operating said carrying devices, and a device operated by said line-space mechanism for connecting said carrying devices with said motor, said device including carriage-carried members operable to connect said motor with said carrying devices for a 85 complete cycle of operation of said device.

carrying devices, but incapable of maintaining such connection for a second cycle.

26. The combination with a typewriting mechanism including a carriage, a line-spacing device, and an operating handle for said device movable relatively thereto for returning the same to begin a new line, of a computing mechanism having a general operator, and means to enable said handle in its movement relative to said carriage to effect a solitary complete cycle of movement of said general operator; said carriage being returnable by said handle after the completion of the relative movement of the latter, and the general operator being out of control of said handle while it returns the carriage; whereby the handle may be manipulated both to start the general operator and return the carriage, without causing repeated operations of the general operator during the time that the handle remains in its carriage-returning position or relation.

27. The combination with a typewriting mechanism including a line-spacing mechanism, of a handle movable to operate the line-spacing mechanism, a computing mechanism having a general operator, and means to enable said handle in its said movement to effect a solitary, complete cycle of movement of the general operator, said means including a trip or release operable by said handle during such movement, whereby the operator is rendered capable of coming only momentarily under the control of said handle, so that the handle if held in operated position, is prevented from causing repeated operations of the general operator; the latter having means to bring itself to a stop at the conclusion of its cycle of operation.

28. The combination of a typewriting mechanism including a carriage, line-spacing mechanism, a handle movable relatively to the carriage in one direction to operate said line-spacing mechanism, a computing mechanism having a general operator, and means exclusive of said line-spacing mechanism to enable said handle in its movement in said direction to effect a cycle of movement of said general operator, said handle being capable both of remaining in operated position and of returning to normal position independently of said general operator.

29. The combination with a typewriting mechanism including a carriage, of a computing mechanism having a general operator, a controlling device to effect a cycle of movement of the general operator, a handle movable relatively to the carriage for returning the carriage to position to begin a new line, a trip arm operated by said handle during its movement relatively to the carriage and freed from the influence of the handle before the latter has completed its movement relatively to the carriage, and operating connections between said trip arm and said

controlling device, whereby the handle may be operated to cause a single cycle of movement of the general operator and return the carriage without repeated movement of the general operator.

30. The combination with a typewriting mechanism including a carriage, of a line-spacing mechanism, a lever on the carriage movable relatively thereto to operate the line-spacing mechanism and operable to return the carriage, a computing mechanism having a general operator, power means to drive the general operator, a controlling device operable to effect a driving connection between the power means and the general operator and thereby cause a single cycle of movement of the general operator, a trip device operated by said lever during its movement relative to the carriage in one direction and free of the influence of said lever except during said movement in one direction, and connecting means between said trip device and said controlling device to operate the latter, whereby said lever may be operated to return the carriage and operate the line-spacing mechanism without causing repeated operations of the general operator.

31. In a combined typewriting and computing machine, the combination with a carriage, of a handle movable relatively thereto for returning the carriage to position for commencing a new line, a computing mechanism having a general operator, a controlling device for effecting a single cycle of movement of the general operator, an arm in the path of said handle and operated thereby during the movement of the handle in one direction relative to the carriage, and operating connections between said arm and said controlling device, said connections comprising means to permit the return of said handle without affecting said controlling device, whereby said handle may be operated to start the general operator and to return the carriage, and the handle again returned to its initial position without causing repeated operations of the general operator.

32. In a combined typewriting and computing machine, the combination with a carriage, of a handle for returning the carriage to position to commence a new line, said handle movable relatively to the carriage, a computing mechanism comprising a general operator, a controlling device for the general operator operable to effect a cycle of movement of the general operator, a trip device in the path of said handle, a bar on the machine frame, a finger operatively connected with said trip device and maintained in operative relation to said bar during the travel of the carriage, said bar movable by said finger when the trip device is operated, and a connection between said

2
bar and said controlling device, said trip device being operable by the handle during the movement of the handle relative to the carriage in one direction to cause the operation of said controlling device, and being taken out of the control of said handle before the latter completes its movement relative to the carriage, and being maintained out of control of said handle until the latter has been returned and again operated in a forward direction, whereby a repeated operation of the general operator during the return of the carriage is prevented, and a line-spacing mechanism operated by said handle during its forward movement relative to the carriage.

33. In a combined typewriting and computing machine, the combination with a carriage, of a handle for returning the carriage to position to commence a new line, said handle movable relatively to the carriage, a computing mechanism comprising a general operator, a controlling device for the general operator operable to effect a cycle of movement of the general operator, an arm in the path of said handle, a bar on the machine frame, a finger operatively connected with said arm and maintained in operative relation to said bar during the travel of the carriage, said bar movable by said finger when said arm is operated, a connection between said bar and said controlling device, said arm being operable by the handle during the movement of the handle relative to the carriage in one direction to cause the operation of said controlling device, and being taken out of the control of said handle before the handle completes its

movement relative to the carriage, and being maintained out of control of said handle until the latter has been returned and again operated in a forward direction, whereby a repeated operation of the general operator 40 during the return of the carriage is prevented, and a line-spacing mechanism operated by said handle during its forward movement relative to the carriage.

34. In a combined typewriting and computing machine, the combination with a carriage, of a handle for returning the carriage to commence a new line, said handle movable relatively to the carriage, a computing mechanism comprising a general operator, 45 a controlling device operable to effect a cycle of operation of the general operator, an arm in the path of said handle, a rock shaft operated by said arm, a finger on said rock shaft operated by said arm, a swinging bar on the machine frame and in operative relation to said finger during the return of the carriage, and connections between said bar and said controlling device for operating the latter, said arm operable by the said handle during the movement of the handle in one direction to rock said rock shaft, and through said connections to effect the operation of the general operator, said arm being ineffective to rock said rock shaft during the 50 return of said handle.
